UNITED STATES PATENT OFFICE.

ELIEL L. SHARPNECK, OF WINTHROP, MASSACHUSETTS, ASSIGNOR TO S-M-P WOOD HEEL COMPANY, OF HAVERHILL, MASSACHUSETTS, A CORPORATION OF MASSACHUSETTS.

SHOE AND HEEL THEREFOR.

1,288,233.

Specification of Letters Patent. Patented Dec. 17, 1918.

Application filed April 19, 1915. Serial No. 22,271.

To all whom it may concern:

Be it known that I, ELIEL L. SHARPNECK, a citizen of the United States, residing at Winthrop, in the county of Suffolk and 5 State of Massachusetts, have invented certain new-and-useful Improvements in Shoes and Heels Therefor, of which the following is a specification, reference being had to the accompanying drawings, forming part 10 thereof.

This invention has reference to improvements in shoes or boots and in heels therefor.

One object of the invention is to so construct a boot or shoe that the heel seat of 15 the sole may retain its original thickness at the edge.

Another object of the invention is to so construct a boot or shoe that the heel thereof may be adjusted relative to the heel seat 20 of the sole and to the counter which has heretofore been impossible whereby the outer surface of the heel may merge more exactly into the curve of the counter.

Another object of the invention is to so 25 construct a heel for boots or shoes that, when said heel is made of wood tendency to split the heel by pressure from the counter is eliminated.

Another object of the invention is to simplify the construction of the heel, thereby 30 to reduce the cost of manufacturing the boot or shoe.

Other objects of the invention will appear from the following description.

35 The invention consists in the improved shoe having the heel seat received by the improved heel frame.

The invention also consists in the improved heel.

40 The invention also consists in such other novel features of construction and combination of parts as shall hereinafter be more fully described and pointed out in the claims.

45 Figure 1, represents a side elevation of parts of a shoe illustrating this invention.

Fig. 2, represents a sectional view of the same taken on line 2—2, Fig. 1.

Fig. 3, represents a plan view of the improved heel to show the heel seat frame.

50 Fig. 4, represents respectively plan and sectional views of a heel seat as heretofore constructed to receive a heel.

Fig. 5, represents similar views of the heel seat used in the improved shoe. 55

Similar characters of reference designate corresponding parts throughout.

In the manufacture of shoes having heels of the variety known as French heels, Cuban 60 heels and modifications thereof it has been customary to make the heels of wood with concavities to receive the heel seats of the shoe soles.

To facilitate the cutting out of said concavities the grain of the wood of 65 said heels usually extends transversely of the height of the heel and lengthwise of the shoe and the edge of said concavity must of necessity be thick in order to retain some strength of the material.

In order to accommodate these thick edges of the heel concavity it has been necessary to place the heel 70 top against the heel seat *a*, Fig. 4, and mark the location for the shoulders *b*, *b*, then cut away the heel seat to form such shoulders and at or about the same time to skive the 75 edge of the heel seat to conform it to the concavity of the heel.

In this process the stitches securing the heel seat to the counter portion of the shoe often were cut thus 80 practically destroying this portion of the shoe.

Another objection has been that the pressure of the counter tends to spread the 85 concave top of the heel which often splits along its grain particularly at the edges of the concavity.

In carrying my invention into practice one of my objects has been to produce a shoe 90 having better wearing qualities and of better appearance than those heretofore constructed and to reduce the cost of manufac-

ture. To this end I construct a shoe 10 having the counter 11 and the heel seat 12 having edges which are the full thickness 95 of the sole 13 and are approximately par-

allel at 14, 14 and then curve as at 15, see 95 Fig. 5.

In conjunction with the shoe thus de- 100 scribed I use the heel 16 which preferably is of wood or other suitable material adapt-

ed to receive securing nails. To this heel 16 I attach the flat frame plate 17 prefer- 105 ably cut away as at 18, 19, to permit the passage of securing nails, and having the flaring lip 20 the front ends 21, 21 of which are spaced apart substantially the width of the heel 16 and are adapted to receive be-

tween them the edge portions 14, 14 of the heel seat 12. This heel frame is or may be of comparatively thin metal and after its attachment to the heel a finish covering 22 is applied to the heel 16 and to said frame, the lower edges of this covering are turned against the lower end of the heel 16, and secured, and the tread piece 23 is secured in place; the upper edge portions of the covering are turned inward over the edge of the lip 20 and secured, thus constituting a heel constituted by different materials having the unitary covering 22 and having a receptacle for the heel seat adapted to be flexed, as to its edge, to conform to the shape of the shoe counter against which the covered lip 20 is secured.

In the application of this improved heel to a shoe no cutting of the heel seat shown in Fig. 5 is necessary. The heel plate is placed flat-wise against the surface of the heel seat 12 with the lip 20 embracing the rear portion of the heel seat and the ends 21, 21 of said lip at the edges 14, 14 of the heel seat. The heel is then readily adjusted along the heel seat until the covered edge of said lip 20 is brought closely against the curved counter portion of the shoe and, in such adjustment, the ends 21, 21 of said lip closely hug the edges 14, 14 of the heel seat. After such adjustment of the heel nails are driven through the heel portion of the shoe into the heel 16 which nails act to draw said heel and its frame closely to the shoe and to secure all of these parts together.

The height of the lip 20 is preferably only such as will accord with or follow the curve of the counter portion of the shoe but said lip may be of a sufficient height to assist in sustaining the shoe counter or to contribute to the stiffening of the shoe coun-

ter, and having a tendency to resist the breaking down of the counter without being unduly rigid.

It is quite essential that the heel frame 45 for the heel seat should not be of a size or shape materially to change the ordinary shape of the heel particularly when said heel and frame are covered. I have found it desirable to make this heel frame plate 50 17 and its lip 20 of comparatively thin sheet metal but it is evident that, when preferred, other material may be used. I also consider the heel 16 and its frame 17, 20, having the unitary covering 22 of importance 55 as otherwise the line of juncture between said heel and said frame might be objectionable in appearance.

The covering 22 may be of leather, fabric, celluloid or any other material known in this 60 art and the term "unitary" used herein with reference to such covering refers more particularly to the exposed portions at the sides and rear of the heel. In shoes having what is known as the full "Louis" heel the front 65 portion or surface of the heel may be covered as is usual, by a split from the sole, without departing from the spirit of this invention.

Having thus described my invention I 70 claim as new and desire to secure by Letters Patent.

A shoe comprising a sole having a heel seat, of a thickness throughout uniform with the sole, a heel permanently and directly attached to said heel seat and having an upstanding lip closely receiving and confining the side edges of said heel seat, and a unitary covering for said heel and said lip, said covering turned inward between 75 80 the edge of said lip and said counter.

ELIEL L. SHARPNECK.
